JACK CONSTRUCTION

Achille Kais, Detroit, Mich.

Application February 16, 1945, Serial No. 578,229

3 Claims. (Cl. 254—111)

This invention relates to lifting jacks, the primary object of the invention being to provide a lifting jack including lifting and holding pawls, operated by a vertically swinging lever, thereby providing a jack requiring appreciably less power for the operation thereof, than is required in the operation of the well known screw-type jack.

An important object of the invention is to simplify the construction of the pawls and the spring controlling the pawls, the simplification of the spring and pawl construction, reducing the cost of production by reducing the number of parts, required in the manufacture of the jack.

A further object of the invention is to provide a lifting jack wherein the lifting power directed to the jack, is applied directly under the head load, providing a more direct lift than is possible with jacks of known construction.

Still another object of the invention is to provide a trip pawl mounted in such a way that the action of the lifting and holding pawls of the jack may be reversed and automatically controlled by the rocking movement of the operating lever, reversing the action of the jack to lower the lifting bracket and its load.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing:

Figure 1 is an elevational view of a jack constructed in accordance with the invention, parts thereof being shown in section.

Figure 2 is a sectional view taken approximately on line 2—2 of Fig. 1.

Figure 3 is an elevational view illustrating the reversing pawl as operated to lower the lifting head of the jack.

Figure 4 is a fragmental elevational view illustrating the connection between the rack bar and base of the jack, the view being taken at right angles to Fig. 1.

Figure 5 is a plan view of the lifting pawl of the jack.

Figure 6 is a plan view of the holding pawl of the jack.

Referring to the drawing in detail, the base of the jack is indicated by the reference character 5, and as shown is provided with a substantially T-shaped upstanding flange 6, providing spaced

walls, for the reception of the rack bar 7 which is substantially T-shaped in cross-section. In order that the rack bar 7 may be removably secured to the base, a cotter key indicated at 8 is provided, and extended through registering openings in the rack bar and flange 6.

The rack bar 7, provides a support for the load head 9, which is constructed to conform to the shape of the rack bar, the load head having openings so that it will slide over the rack bar, as clearly shown by Fig. 1 of the drawing.

Forming a part of the load head, is a bracket 10 which is formed with a supporting arm 11 that extends downwardly and curves inwardly towards

10 the rack bar, where it merges into the load head.

15 A bearing indicated at 12 is formed in the sup-

porting arm 11, at a point below the bracket 10,

where the forked end 13 of the lever 14 is pivot-

20 ally connected. As clearly shown by Fig. 2 of the

drawing, the forked end of the lever 14, straddles

15 the rack bar and load head, to the end that move-

ment of the lever 14 will be balanced, preventing

25 twisting of the jack when pressure is brought to

bear on the lever, in the operation of the jack.

20 The holding pawl is indicated by the reference

character 15 and embodies side arms which are

connected at their free ends by a connecting bar

25 16, which connecting bar is adapted to engage the

teeth 17 of the rack bar. The arms of the hold-

30 ing pawl 15 are curved inwardly towards the rack

20 bar so that the contact between the connecting

35 bar and the teeth of the rack bar, will be at a

point below the pivot 18 of the holding pawl 15.

30 Pivotedly mounted within the forked end of the

35 lever 14, is a lifting pawl 19 which also embodies

curved arms connected at their free ends by means

40 of a connecting bar 20.

The pawls 15 and 19 are normally urged to-

45 towards the teeth of the rack bar 7, by means of

the spring 21 which is shown as secured to the

arm 11 of the load head 9, the spring being ex-

40 tended downwardly and upwardly between the

arms of the pawls, where it contacts the connect-

45 ing bars of the pawls, normally restricting move-

ment of the pawls, away from the rack bar. Dis-

40 posed exteriorly of the load head 9, and being

45 pivotally connected therewith, is a reversing pawl

50 22 which is formed with a curved edge 23 adapted

45 to be engaged by the screw pin 24 that extends

40 into a threaded opening formed in one side of the

45 forked end of the lever 14, the length of the pin

55 being such that the inner end thereof may extend

45 to a point directly over the curved edge. Thus

50 it will be seen that when the screw pin 24 has

55 been positioned as shown by Fig. 2 of the draw-

ing, and the lever is moved upwardly, the upper end of the reversing pawl will be swung outwardly, while the lower end thereof will move into engagement with the connecting bar 20 of the lifting pawl 19, forcing the pawl 19 away from the teeth of the rack bar engaged thereby. The lever 14 is now pressed downwardly with the result that the screw pin 24 will now move downwardly over the curved edge of the reversing pawl, allowing the pawl 19 to move into contact with the rack bar. As the reversing pawl moves so that the upper end thereof contacts the holding pawl 15, the holding pawl will be moved out of engagement with the rack bar, allowing the load head to drop into the adjacent lower space between teeth of the rack bar. By repeating this operation, the load head may be moved to its lowermost position to release it from the load.

On operating the jack to elevate the load head in jacking up a load, the screw pin is removed, and the reversing pawl 22 remains in the position as shown by Fig. 1 of the drawing. With the reversing pawl in this position, it will be seen that when the lever 14 is pressed downwardly, the load head is elevated or raised on the rack bar. It follows that because of the spring pressure against the pawl 15, the pawl 15 will move into a notch or recess between teeth of the rack bar. During the upward movement of the lifting head, the weight of the load is supported by the lifting pawl 19. The lever 14 is now elevated, with the result that the pawl 19 moves over the teeth of the rack bar and again moves into a notch or recess between adjacent teeth. Upon downward movement of the lever the load head is again elevated, the pawl 15 again taking a position in a notch or recess of the rack bar above the previous point of contact with the rack bar by the pawl. As this operation is continued, the load head is elevated to the desired position.

In view of the foregoing detailed disclosure, it is believed that a further description as to the operation of the jack is unnecessary.

What is claimed is:

1. In a jack, a vertical rack bar, a movable load head mounted for movement longitudinally of the rack bar, a load-engaging bracket forming a part of the load head, a lever having a forked

end adapted to straddle the rack bar and load head, means for pivotally connecting the forked end of the lever to the load head at a point directly under the bracket, a pivoted lifting pawl mounted on the forked end of the lever at a point spaced from the pivoted end of the lever, a holding pawl pivotally mounted on the load-engaging bracket, means for normally urging the pawls into engagement with the teeth of the rack bar 5

10 moving the load head longitudinally of the rack bar when the lever is rocked vertically, a reversing pawl mounted on the load head, said reversing pawl adapted to alternately move the lifting pawl and holding pawl out of contact with the 15 teeth of the rack bar when the lever is rocked vertically, thereby lowering the load head, and a removable pin extending from the lever and adapted to engage the reversing pawl, operating the reversing pawl.

2. In a lifting jack, a vertical rack bar, a movable load head mounted on the rack bar, an operating lever pivotally connected with the load head, a lifting pawl connected with the lever, a holding pawl mounted on the load head, a double-ended reversing pawl mounted on the load head, said reversing pawl having a curved edge, a pin carried by the lever and adapted to move over the curved edge of said reversing pawl, alternately moving the ends of the reversing pawl 35 into engagement with the lifting pawl and holding pawl as said lever is rocked vertically, whereby said lifting pawl and holding pawl are alternately moved into engagement with the teeth of the rack bar, lowering the load head.

3. In a lifting jack, a vertical rack bar, a movable load head mounted on the rack bar, an operating lever pivotally connected with the load head, a lifting pawl connected with the lever, a holding pawl connected with the load head, a spring engaging the pawls and adapted to urge the pawls into engagement with the teeth of the rack bar, a double-ended reversing pawl mounted on the load head and adapted to alternately move the lifting pawl and holding pawl out of engagement with the rack bar, and means carried by the lever for operating the double-ended pawl when the lever is rocked, lowering the load head.

ACHILLE KAIS.
